(57) **CLAIM**

The ornamental design for barrel mounted Picatinny rail, as shown and described.

DESCRIPTION

This application is related to U.S. patent application Ser. Nos. 29/420,687, entitled Universal Sling Mount for Picatinny Rail; 29/420,689, entitled Barrel Mounted Picatinny Rail; 29/420,697, entitled Barrel Mounted Picatinny Rail—all of which were simultaneously filed with the present application on May 11, 2012.

FIG. 1 is a top view of the barrel mounted Picatinny rail showing a new ornamental design thereof;

FIG. 2 is a bottom view of the barrel mounted Picatinny rail shown in FIG. 1;

FIG. 3 is a front elevation view of the barrel mounted Picatinny rail shown in FIG. 1;

FIG. 4 is a rear elevation view of the barrel mounted Picatinny rail shown in FIG. 1;

FIG. 5 is a left side elevation view of the barrel mounted Picatinny rail shown in FIG. 1;

FIG. 6 is a right side elevation view of the barrel mounted Picatinny rail shown in FIG. 1; and,

FIG. 7 is a rear perspective view of the barrel mounted Picatinny rail shown in FIG. 1.
